UNITED STATES PATENT OFFICE

92,693

DESIGN FOR A BEER MUG

Will Low Bacher, Rock Tavern, N. Y., assignor to White Cloud Farms Inc., Rock Tavern, N. Y., a corporation of New York

Application April 12, 1933, Serial No. 47,765

Term of patent 7 years

To all whom it may concern:

Be it known that I, WILL LOW BACHER, a citizen of the United States and residing at Rock Tavern, in the county of Orange and State of New York, have invented a new, original, and ornamental Design for a Beer Mug, of which the following is a specification, reference being had to the accompanying drawing, forming part thereof.

Fig. 1 is a perspective view of a beer mug showing my new design, and

Fig. 2 is a perspective view showing the opposite side of the mug.

I claim:

The ornamental design for a beer mug as shown.

WILL LOW BACHER.
